UNITED STATES PATENT OFFICE

BION C. PLACE, OF DETROIT, MICHIGAN, ASSIGNOR OF ONE-HALF TO GEORGE E. GAGNIER, OF DETROIT, MICHIGAN

PANEL FOUNDATION MAKING

Application filed July 2, 1931. Serial No. 548,464.

This invention relates to the art of making foundations for automobile or similar panels of the kind that are utilized to finish the interior of bodies of any character.

5 Trim panels for use in finishing automobile or similar bodies generally consist of a relatively stiff fibrous foundation and a suitable fabric covering, applied to one face of the foundation and lapped around the edges 10 thereof. The panel thus formed is applied to a supporting structure by disposing the rear or uncovered face thereof adjacent the supporting structure so that only the covered face and edges are visible. When ornamentation 15 of the panel is desired, it has been the practice heretofore to apply what is known in the art as a riser to the foundation of the panel prior to the application of the fabric covering thereto. Such risers have sometimes 20 been constructed of fibreboard or cardboard in strip form. The cardboard or fibreboard risers are unsatisfactory because they do not present the rounded corners desired to secure the best ornamental effect, and because they 25 are so flimsy because of their narrow width that they furnish virtually no supplemental strength to the panel that is weakened by the means of attachment of the risers thereto, which penetrates both the riser and the foundation. 30

It has also been proposed to construct the risers of rubber, but this material, in addition to its high cost, is extremely flexible and accordingly it likewise does not stiffen the 35 fibreboard foundation at the point at which it is weakened by the staples or stitching that is utilized to secure the riser to the foundation.

In other instances it has been proposed to 40 form the riser as an integral part of the foundation by corrugating and embossing upward projections in the foundation at the points desired. This practice is resorted to in an endeavor to avoid the necessity for 45 weakening the foundation by attaching the risers as separate strips. The formation of such corrugations, however, likewise weakens the foundation, since fibrous material is not inherently adapted for corrugation in 50 view of the fact that the material can not

be stretched materially without weakening it seriously even if it is not ruptured by the corrugating.

This invention aims to improve the foundations for ornamented panels by using a riser 55 which, by virtue of its inherent characteristics, serves to stiffen the panel at the point of attachment of the riser so that the foundation is stiffer at the said point of attachment than at other portions of the foundation, 60 though the foundation has been perforated by the means that is utilized to attach the risers thereto.

A further object of the invention is to provide a foundation panel ready for the application 65 of the covering material, including separately attached riser strips made of compacted paper shaped in such a way as to provide a flat surface for firm contact with the foundation over a wide area and to present 70 a rounder surface to the covering material subsequently applied thereto.

Another object of the invention is to provide an improved riser for the foundations 75 of automobile or similar trim panels, made of a plurality of strands of kraft paper twisted together and subsequently compressed or compacted and reshaped to provide a riser in the approved form that may be produced at an extremely low cost, though 80 possessing characteristics superior to the characteristics of the material heretofore used for this purpose.

Another object of the invention is to provide an improved method of reinforcing the 85 foundation of an automobile or similar panel by utilizing the risers that serve the purpose of ornamenting the panel in its completed form.

Still another object of the invention is to 90 provide an improved method of applying strips in the form of relatively laterally inflexible risers to a foundation for an automobile or similar panel, whereby neat corner joints may be made between strip sections that 95 extend at an angle to each other.

Further objects of the invention will appear as a description thereof proceeds with reference to the accompanying drawing in 10 which:

Figure 1 is a fragmental view of a partially completed riser and reinforcing strip, one end of the incomplete riser being untwisted to show the construction thereof.

5 Figure 2 is a sectional view taken on the plane indicated by the line 2—2 in Figure 1.

Figures 3 and 4 are respectively plan and sectional views of the riser produced by compacting and reshaping the twisted paper 10 product illustrated in Figures 1 and 2.

Figure 5 is a plan view of a foundation for an automobile or similar body showing the mode of application of the riser or strip sections.

15 Figure 6 is a fragmental view of the foundation illustrated in Figure 5 on an enlarged scale, showing the relation of the lapped edges of adjacent sections of the riser, and illustrating how the mitre joint is formed between said sections of the riser.

20 Figure 7 is a fragmentary view similar to Figure 6 showing a completed corner joint.

Figure 8 is a plan view of a foundation with the riser sections attached thereto in 25 completed form.

Figure 9 is a sectional view taken on the plane indicated by the line 9—9 in Figure 8.

30 Figure 10 is an enlarged sectional view of the fragmentary portion of the panel showing the covering material applied over a riser section.

Like reference characters indicate like parts throughout the several figures.

35 The combined riser and foundation reinforcing strips constituting an essential part of the present invention are preferably each formed from a plurality of strips of paper twisted together and then compacted and reshaped so as to provide a finished product 40 having a hard and dense interior. Such a strip possesses great strength and resistance to lateral bending and is relatively stiff when it is sought to curve it toward or away from the foundation to which it is to be applied. 45 Preferably, the strip is formed by twisting together, in the manner of a rope, four strands of paper designated by the numerals 11, 12, 13 and 14 in Figure 1.

50 The paper strands may be first individually twisted before the four strands are twisted together to form a loose rope-like structure. In order to soften the paper and enable it to be readily twisted into this form, the paper is moistened before the strands are twisted individually or together. Paper of various 55 kinds may be used for the formation of the strips in question. Preferably kraft paper is used. It has been found that kraft paper, eight thousandths of an inch thick and two 60 and one-half inches wide is well adapted for the formation of the strands. After the strands of paper have been individually twisted they are twisted together to form a loosely wound cable 15 illustrated in Figure 1. 65 Said paper cable or cord is roughly circular

in cross-section and is made up of indefinite length. While the cord or cable thus formed is still moist, it is passed through shaping rollers and subjected to great pressure to reshape and compress or compact the fibrous 70 material entering into the construction of the cord or cable to produce a strip 16, Figures 3 and 4, having a flat surface 17 and a curved surface 18. During this operation of reshaping and compacting or compressing the strips, such strips are subjected to pressure sufficient 75 to greatly reduce the cross-sectional area of the strip and to compact the structure so that a stiff and hard strip is formed having characteristics quite similar to that of wood, 80 without the liability of splitting when fasteners are driven therethrough. During the operation of pressing and reshaping the strips all the moisture is extracted therefrom so that at the completion of the operation the 85 strip is virtually dry.

The compressed paper strip made in the manner just described has been found to be admirably adapted to serve the double function of reinforcing fibre foundations, and, 90 at the same time, to serve the purpose of providing the riser or elevation for the fabric covering subsequently to be applied to the foundation. Inasmuch as the hard and dense material made in the manner just described 95 cannot be bent in the direction of its major dimension at sharp angles, the strip is applied to the foundation in separate relatively straight or gradually curved lengths after the manner particularly illustrated in Figures 5, 6 and 7 of the drawing. As shown 100 in these figures, a section 19 of a strip of the kind just described is disposed on the foundation and stapled thereto by means of staples 20, Figure 6, applied thereto at intervals along the length of the strip. The strip 19 generally parallels one edge of the foundation. Further straight sections 21, 22 and 23 and curved strip 24 are similarly applied to the foundation, preferably by stapling, 110 though said strips may be attached in any other approved manner. As illustrated in Figures 5 and 6, the strips are cut of such length that the ends of adjacent strips overlap and 115 underlap respectively sufficiently to permit the formation of a mitre or bevel joint between the adjacent ends of the strips, as illustrated in detail in Figures 6 and 7, in which one corner of the foundation is illustrated 120 to show the mode of making one of the joints between the adjacent strips. In Figure 6, the strips 22 and 19 lap as illustrated and said strips are attached to the foundation so that the end staples 20' and 20'' on the several 125 strips are disposed close to the point of intersection of said strips. The end of strip 19 underlies the end of strip 22 as illustrated in this figure. In order to complete the bevel joint, after the strips have been firmly attached to the foundation as just described, 130

the overlapping edges are cut on the line indicated by the numeral 25 in Figure 6 by any suitable sharp instrument, and the severed ends, which are of quadrilateral or triangular form, are removed permitting the end of the strip 22 to rest on the face of the foundation, with its beveled edge in snug engagement with the beveled edge of the strip 19, as illustrated in detail in Figure 7. Similar mitre or beveled joints may be formed at all of the points of connection between the various strips that form a part of the riser. The reinforcing strips just described may be applied in the manner pointed out to foundations constructed of any material, but preferably fibreboard is used for this purpose in accordance with general practice. The fibreboard is stamped out in the outline of the completed surface to which the panel is to be applied. If the panel is to be applied to an automobile door, for example, it will assume an outline similar to that shown in Figures 5 and 8, that is, a generally rectangular form having one of the corners cut out on a curve 26. It will be observed that all the reinforcing strips generally parallel the edges of the foundation and that when a curve on a large radius forms a part of an edge of the foundation, the strip which is capable of being laterally bent on such curves follows in general the curve at said edge of the foundation.

If desired, the foundation may be provided with a multiplicity of specially formed openings 27 arranged at regularly spaced intervals around the periphery, except in any portions thereof that are otherwise held in position, as by a molding forming a part of the supporting structure. These openings are formed, as illustrated in Figures 5 and 8, to receive a spring fastener after the covering material has been applied to the outer face of the foundation, as described in my patent #1,722,944 granted July 30, 1929. When such openings are used it will be observed that the reinforcing strips stiffen the margin of the panel in which the openings are formed, thereby strengthening the foundation and stiffening it to resist bending thereof where it is weakened by the formation of the fastener-receiving openings. The foundation may be provided with a further opening 28 for the passage of the window operating mechanism, and a further opening 29 for the door fastener operating mechanism.

If desired to further strengthen the panel and to further enhance the appearance thereof after completion, it may be provided with further reinforcing strips in the form of relatively short sections 30 and 31, Figure 8, joined by a sharply curved short section 32, between which mitre joints will be formed between the ends of the sharply curved strip 32 and the sections 30 and 31 in the manner

heretofore described. Inasmuch as the short strip 32 is curved rather sharply for ornamental purposes, said strip is preferably provided with the desired curvature, during the course of manufacture of the strips by curving the strip laterally, while it is still soft, in the process of manufacture. The strip curved in this manner may be conveniently handled by permitting the spiral formed by the curving just described to assume an indefinite length permitting adjacent convolutions to contact with each other, forming a reel that may be conveniently handled and shipped to the point of application of the short cut curved sections 32. It will be observed that inasmuch as the openings 28 and 29 are formed between the reinforcing strip section 22 on the one side of said openings and the sections 30, 31 and 32 on the other side of the openings that the panel is stiffened in the portion thereof in which the openings are made, and at the point thereof at which it has its maximum width.

It will be observed that the flat surface 17 of the strip sections rest on the foundation and cover a substantial area thereof, each providing a firm contact with the surface of the foundation after the strip section has been stapled thereto. The stiffened foundation accordingly becomes, after completion of the application of the strip, a substantially integral structure, the strip sections preventing the warping or bulging of the foundation when put into use. At the same time, in view of the wide area of contact, the panel is strengthened at the point where it would otherwise be weakened by the penetration of the staples 20. The rounded portions of the strips permit the fabric subsequently applied to the foundation to be smoothly applied thereover as illustrated in Figure 10, in which the numeral 33 designates the usual fabric covering for the foundation that is stitched to the foundation by lines of stitches generally paralleling the edges of the strip or riser following usual practices, said lines of stitching being designated by the numerals 34 and 35. The edge of the fabric is lapped over the edge of the foundation and secured to the back thereof as indicated at 36, also following the established practices of the art.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:—

1. A foundation for an automobile or simi-

- lar panel comprising a fibrous body shaped to fit the surface to which the panel is to be applied, and a narrow strip of compacted fibrous material secured to said body to stiffen same and to serve as a riser in the ornamentation of said foundation.
2. A foundation for an automobile or similar panel, comprising a fibrous body shaped to fit the surface to which the panel is to be applied, and a narrow stiffening strip of twisted kraft paper secured to said foundation, said strip being compacted to provide wide flat surface for contact with said foundation and to provide an elevated rounded surface, to serve as a riser in the ornamentation of said foundation.
3. A foundation for an automobile or similar panel, comprising a fibrous body cut in the outline necessary to fit the surface to which the panel is to be applied, and a strip of compacted paper attached to said foundation spaced from but generally paralleling the margins of the foundation whereby said strip reinforces the foundation and may serve as a riser in the ornamentation of the panel.
4. A foundation for an automobile or similar panel, comprising a fibrous body cut in the outline necessary to fit the surface to which the panel is to be applied, and a strip of compacted twisted and reshaped kraft paper attached to said foundation spaced from but generally paralleling the margins of the foundation whereby said strip reinforces the foundation and may serve as a riser in the ornamentation of the panel.
5. A foundation for an automobile or similar panel comprising a body of fibrous material provided with fastener receiving openings adjacent the margins thereof, and a stiffening strip of compacted paper attached to said foundation spaced from but generally paralleling said margins, said stiffening strip having a wide flat surface bearing on the body and a rounded raised surface that may be used as a riser in the ornamentation of the panel.
6. A foundation for an automobile or similar panel comprising a body of fibrous material provided with fastener receiving openings adjacent the margins thereof and further openings in the body thereof, and a stiffening strip of compacted paper extending across the body in both directions and on opposite sides of said openings in said body and being secured thereto, said strip having flat surfaces contacting with said body and raised rounded surfaces so that it may serve as a riser in the ornamentation of the panel.
7. A combined riser and reinforcing strip for the foundation of an automobile or similar trim panel, consisting of a narrow strip of compacted paper having a flat surface for firmly contacting the foundation and a rounded surface for ornamentation of the panel.
8. A combined riser and reinforcing strip for the foundation of an automobile or similar trim panel, consisting of a narrow strip of compacted paper having a flat surface for firmly contacting the foundation and a rounded surface for ornamentation of the panel, said strip being formed of strands of kraft paper twisted together and subsequently reshaped and compacted to form said surfaces.
9. The method of attaching stiffening strips generally paralleling the edges of a foundation for a trim panel, which consists in applying a plurality of relatively straight strips to the foundation so that a separate strip is used to generally parallel each side of the foundation, and forming a miter joint between the adjacent edges of the separate strips by permitting said strips to lap after completion of the attachment thereof by cutting said overlapping edges on a bias.
10. A foundation for a trim panel comprising a fibrous body and a reinforcing strip secured to said body and generally paralleling each edge of said foundation, said strip including a separate section for each edge of the foundation, the end of each section of said strip being joined to an adjacent section by a miter butt joint.

In testimony whereof I affix my signature.
